UNITED STATES PATENT OFFICE.

GEORGE B. STREIT, OF DETROIT, MICHIGAN.

FOLDING BOX.

968,286.

Specification of Letters Patent. Patented Aug. 23, 1910.

Application filed July 29, 1909. Serial No. 510,311.

To all whom it may concern:

Be it known that I, GEORGE B. STREIT, a citizen of the United States, residing at Detroit, county of Wayne, State of Michigan, have invented a certain new and useful Improvement in Folding Boxes, and declare the following to be a full, clear, and exact description of the same, such as will enable others skilled in the art to which it pertains to make and use the same, reference being had to the accompanying drawings, which form a part of this specification.

This invention relates to folding boxes or cartons.

It has for its object an improved box made from a single piece of flexible material adapted to completely cover in and enclose the contents, and also adapted when a single fold is raised from its completely folded position to disclose the contents of the box while retaining or holding them in place.

In the drawings:—Figure 1, illustrates the blank. Fig. 2, illustrates the box folded from the blank shown in Fig. 1.

The blank comprises a sheet or strip of flexible material, cardboard or thick paper, cut in the form of a cross shown in Fig. 1. This comprises three sections that form the top and bottom of the box, five sections that form the sides and ends of the box and three flaps to be turned under the goods.

The section 1 forms the lid. The section 2 forms the bottom. The section 3 forms the top of the box engaging closely under the lid. The sections 4, 5 and 6 form the sides of the box in its folded form. The sections 4 and 6 fold closely together. The sections 7 and 8 form the ends of the box and the sections 9, 10 and 11 form inturned flaps that in the folded box lie closely adjacent to the bottom 2 and underneath any articles that may be packed in the box. The section 3 is provided with a central inspection opening 12 and with corners *a*, *b*, *c* and *d* that extend from the ends and sides of this covered section 3 inward to the central opening 12. In those corners which are next ad-

jaacent to the bottom 2 and contiguous to the side section 5, are made slits 13 and 14 and the sides of the section 1 are cut at 21 and 22 to a width equal to or slightly less than that across the section 3 from the end 23 of the slot 14 to the end 24 of the slot 13. The corners beyond the points 21 and 22 project to form holding ears 25 and 26 that engage under that portion of the section 3 which lies between the slot and the corner of the completed carton and forms an interlocking fastening that is sufficiently secure for practical purposes.

In the folded carton shown in Fig. 2 the space or chamber within the box is accessible through the opening 12, but the main purpose of the opening 12 is to furnish inspection to the contents of the box which are retained therein, and protected from dirt and the contact of the fingers of the user. Articles exhibited for sale in them may be readily exhibited but may not be readily handled, and the entire package is so readily applied and so cheap in production that the articles exhibited for sale in the package are delivered with the carton and without delivering the article therefrom.

What I claim is:—

A single piece carton for goods comprising a top, a bottom, sides, ends, a cover flap and infolds engaging against the bottom and adapted to engage under the contents of the box, the said top having a circular opening of a diameter slightly less than the distance from side to side of the carton and inclined slits across the two corners of the part surrounding said opening, and the cover flap being of substantially the same width of the top and having corner ears adapted to engage in said slits and an outwardly extended edge between said ears to overlie the periphery of said opening between said ears.

In testimony whereof, I sign this specification in the presence of two witnesses.

GEORGE B. STREIT.
